WELLHEAD CONNECTION

Arthur J. Penick and Kirby T. Penick,
Houston, Tex.Original application May 25, 1931, Serial No.
539,841. Divided and this application De-
cember 18, 1933, Serial No. 702,934

2 Claims. (Cl. 166—14)

This invention relates to a well head connection.

The subject matter of this invention has been divided out from our Patent 2,016,454 of October 5, 1935.

An object of the invention is to provide a well head having a Christmas tree or other similar pipe connection mounted to swivel thereon about an approximately vertical axis so that the Christmas tree or other connection may be adjusted and secured in any desired position.

Another object of the invention is to provide, in a well head connection, novel means for supporting the tubing in the well.

With the above and other objects in view, this invention has particular relation to certain novel features of construction, operation and arrangement of parts, an example of which is given in this specification and illustrated in the accompanying drawing wherein.

The figure shows a side elevation of a well head embodying the invention and shown partly in section.

Referring more particularly to the drawing the numeral 1 designates a pipe or casing in a well bore. Attached to the upper end of said pipe preferably by means of a coupling 2, there is a main tubular body 3, connected to the upper end of which there is a slip bowl 4 whose upper end supports a gate valve 5 having the swivel adapter 6 which is attached to the upper end thereof. The slip bowl 4 has an internal downwardly converging seat 7 in which may be located the downwardly tapering slips 8 forming a tubing hanger and the inner faces of these slips may be provided with tubing engaging teeth 9 adapted to engage around the tubing 10 to be supported by the slips 8.

There is a gland composed of upper and lower annular plates 11, 12 with a packing ring 13 between them, said gland being located above the slips 8 and fitting closely around the tubing. A ring nut 14 may be threaded into the upper end of the bowl 4 against the upper plate 11 to secure the gland and slips in place and to expand the packing ring 13 outwardly against the surrounding walls of the bowl 4 and inwardly around the tubing 10 to form fluid tight joints. Other means than those shown may be employed for supporting the tubing, the supporting means constituting no part of the present invention.

Upon the swivel adapter 6 there is a top outlet union 15 whose lower end is enlarged at 16 and on said enlarged portion there is an annular loose flange 17 which is retained in place by set bolts

18. The set bolts extend through said ring and are screwed into the adapter 6 and their upper ends are provided with heads 19 which engage the flange 17.

The lower end of the union 15 and the upper end of the adapter 6 have the facing annular grooves 20 and 21 in which is seated a suitable sealing ring 22, to form tight joints in said grooves.

A suitable connection such as a Christmas tree 10 23, having the lateral branches 24, 24 and the upstanding branch 25, may be connected to the union 15 said branches being equipped with suitable control valves 26. Any other type of connection than that shown may be connected to the union 15.

In case it be desired to adjust said Christmas tree or other connection about a vertical axis the bolts 18 may be loosened and the desired adjustment accomplished and said bolts again tightened. The fluid flowing upwardly from the well may flow up through the tubing 10 and on up through the swivel adapter 6 and through the connection attached to the union 15. The tubing in the well may be readily removed by detaching the swivel adapter 6 and the appendants thereof and by removing the ring nut 14.

The drawing and description disclose what is now considered to be a preferred form of the invention by way of illustration only while the broad principle of the invention will be defined by the appended claims.

What we claim is:

1. The combination with a tubular head adapted to be attached to the casing in a well bore, of a cylindrical slip bowl thereon having a downwardly converging seat therein, and an enlarged counterbore above the seat and whose upper end is reduced and outwardly threaded, slips shaped to fit into said seat and to surround and engage a tubing through said bowl and extended up into the counterbore, a gland in the counterbore supported solely on the slips and composed of upper and lower annular plates with a packing ring between said plates, said gland being fitted closely around the tubing and a ring nut threaded into the upper end of the bowl against the upper plate to secure the gland and slips in place.

2. The combination with a tubular head adapted to be attached to casing in a well bore and having a downwardly converging inside seat, of a cylindrical slip bowl on the head having a downwardly converging seat therein and having an enlarged internally threaded counterbore at its lower end to receive the head and an enlarged 55

counterbore above the seat, the upper end of said bowl being reduced and outwardly threaded to receive a flow controlling connection thereon, slips shaped to fit into the seat of the bowl and to surround and engage a tubing through said bowl and extended up into the counterbore above, a gland on said slips fitted into the upper counterbore and composed of upper and lower annular

plates with packing between the plates, said gland fitting closely around the tubing and a ring nut threaded into the upper end of the counterbore at the upper end of the bowl against the upper plate to secure the gland and slips in place. 5
